US00D570100S

(12) **United States Design Patent** (10) Patent No.: **US D570,100 S**
Chen (45) Date of Patent: ** Jun. 3, 2008

(54) **COVER USED IN ELECTRONIC APPARATUS**

2005/0135603 A1 * 6/2005 Stanford 379/454

(75) Inventor: **I-Ming Chen**, Taipei (TW)

* cited by examiner

(73) Assignee: **Singim International Corp.**, Taipei Hsien (TW)

Primary Examiner—Catherine R Oliver

(74) Attorney, Agent, or Firm—Bacon & Thomas, PLLC.

(**) Term: **14 Years**

(57) **CLAIM**

(21) Appl. No.: **29/269,385**

The ornamental design for a cover used in electronic apparatus, as shown and described.

(22) Filed: **Nov. 30, 2006**

DESCRIPTION

(51) **LOC (8) Cl.** 03-01

FIG. 1 is a perspective view of a cover used in electronic apparatus showing my design;

(52) **U.S. Cl.** **D3/218**

FIG. 2 is a front view thereof;

(58) **Field of Classification Search** D3/218, D3/215, 219, 228, 226, 230, 303, 232–246; 224/240, 914, 904, 675–677, 242, 647, 666–668, 224/197; 379/454–455; 455/550, 575, 90

FIG. 3 is a rear view thereof;

See application file for complete search history.

FIG. 4 is a left side view thereof;
